UNITED STATES PATENT OFFICE.

OSSIAN PARSON, OF SEATTLE, WASHINGTON, ASSIGNOR OF ONE-HALF TO OTTO OLSON,
OF SEATTLE, WASHINGTON.

FUEL TANK.

Application filed July 18, 1927. Serial No. 206,580.

My present invention relates to improvements in fuel tanks especially as used on automotive vehicles, the purpose of the invention being the provision of a tank that is proof against the theft of its contents. As is well known frequent depredations are made upon the gasoline supply tanks of automobiles, by unauthorized siphoning, or otherwise withdrawing, the gasoline from the interior of the supply tank. The primary object of my invention is the provision of means within the tank that will prevent the effective use of a siphoning device or other similar device, by preventing access of such a device to the contents of the tank. In carrying out my invention I locate the theft-preventing device of the tank within the filling opening of the nipple of the tank and preferably weld the device to the tank in order that the device may be firmly and rigidly secured to the face of the tank and form an integral part thereof.

The invention consists in certain novel combinations of parts as will hereinafter be more fully pointed out. In the accompanying drawings I have illustrated the physical embodiment of my invention wherein the parts are combined and arranged according to the best mode I have thus far devised for the practical application of the principles of my invention.

Figure 1 is a sectional detail view of a portion of a tank with the theft-preventing device of my invention applied thereto.

Figure 2 is an enlarged sectional view at line 2--2 of Figure 1.

Figure 3 is a sectional view at line 3--3 of Figure 1.

In carrying out my invention I utilize any of the well known types of gasoline tanks as 1 which is provided with a filling opening and threaded nipple, 2 for the cap 3 that is fashioned with the usual vent opening 4.

In the preferred form of my invention as disclosed in the drawings I utilize a double walled, cylindrical, open, cage having an

outer slotted wall 5 and an inner slotted wall 6, the slots of the walls being arranged in "staggered" positions so that a slot of one wall is on a radial line with a solid portion of the other wall for the purpose of preventing the insertion or introduction of a siphon nozzle, or other device, through the walls of the cage.

The outer vessel is fashioned with a perforated or foraminous bottom 7 and the two walls are joined at the top by means of an annular, horizontal attaching flange 8 that is welded or soldered at S to the inner face of the tank, or the cage may be secured thereto in any other suitable manner. The bottom of the inner vessel as 9 is also perforated in order that no material obstruction will be offered to the gasoline as the tank is being filled in usual manner with the fuel supply.

If desired a filtering fabric may be placed within the cage when the gasoline is being poured therein to strain or filter the gasoline, and of course the fabric is removed after the filling operation.

The double-walled cylindrical cage as thus provided is used as an integral part of the tank, and is effective in the performance of its required functions in preventing the introduction or insertion of any article that could be used to drain or draw off the contents of the tank.

Having thus fully described my invention, what I claim as new and desire to secure by Letters Patent is—

The combination with a tank having a filling opening, of an integral, double walled cage comprising spaced inner and outer slotted vessels, a perforated bottom for the outer vessel, a perforated bottom for the inner vessel spaced above the bottom for the outer vessel, and an annular, imperforate top portion joining the two vessels and welded to the face of the tank.

In testimony whereof I affix my signature.

OSSIAN PARSON.
